ROCK DRILL

Filed July 30, 1931

UNITED STATES PATENT OFFICE

EDWARD F. TERRY, OF PHILLIPSBURG, NEW JERSEY, ASSIGNOR TO INGERSOLL-RAND COMPANY, OF JERSEY CITY, NEW JERSEY, A CORPORATION OF NEW JERSEY

ROCK DRILL

Application filed July 30, 1931. Serial No. 553,938.

This invention relates to rock drills, and more particularly to a guide for rock drills of the type which are mounted in supporting shells whereon they slide to and from 5 the work.

One object of the invention is to minimize the cost of maintenance of rock drills of this type and another object is to equip the rock drill with a guide which may be conveniently 10 attached thereto and which will remain in rigid assembled relationship with respect to the rock drill.

Other objects will be in part obvious and in part pointed out hereinafter.

15 In the drawing accompanying this specification and in which similar reference characters refer to similar parts,

Figure 1 is a longitudinal elevation partly in section of a rock drill constructed in accordance with the practice of the invention,

Figure 2 is an end elevation illustrating the manner in which one end of the guide is secured to the rock drill,

Figures 3 and 4 are transverse views taken 25 through Figure 1 on the lines 3-3 and 4-4 looking in the direction indicated by the arrows, and

Figure 5 is a perspective view of the 30 guide.

Referring more particularly to the drawing, A designates generally a rock drill comprising a cylinder B and front and back heads C and D respectively which may be secured to the cylinder by side rods or bolts 35 E arranged on the opposite sides of the drill.

Within the cylinder B is a reciprocatory hammer piston F having an extension G which extends slidably through chuck mechanism designated generally by H and being 40 arranged in the front head C and in a bushing J disposed in the front end of the cylinder B. The bushing J carries at its front end an external lateral flange K to seat upon the rear end of the front head C.

45 The chuck mechanism H may, as is customary, be rotatable within the front head and the bushing J and, in the present instance, serves as a guide for an anvil block L against which the blows of the hammer piston F are delivered and which serves to

transmit such blows to the working implement O guided by the chuck mechanism H.

In accordance with the practice of the invention and in contradistinction from the usual practice of equipping the cylinder with integral guide ribs to slidably interlock with a mounting, such as a shell P shown in Figure 2, the rock drill is provided with a removable guide Q comprising a beam or plate portion R which, in the assembled position, lies beneath the rock drill and more particularly beneath the cylinder B. The outer sides or edges of the beam R constitute guide ribs S which are adapted to slide in guideways T of the shell P. The beam R may be suitably reinforced by means of integral top and bottom ribs U and V respectively and which preferably extend along the entire length of the beam.

Formed as an integral portion of the beam 70 R and on the front end thereof is a sleeve W which, in the assembled position of the guide, is disposed between the front end of the cylinder B and the rear end of the flange K and has a bore X to receive the portion 75 of the bushing J adjacent the flange K against which the front end of the sleeve seats.

On the rear end of the guide and on the bottom surface thereof is a lug Y having 80 a bore Z to receive a feed nut b which is threaded in a well known manner for engagement with a feed screw c commonly employed for actuating the rock drill A longitudinally of the shell. The feed nut b may 85 be held against rotation in any convenient manner. The rear end of the feed nut b projects rearwardly of the lug Y and has a threaded exterior for the reception of a nut d whereby the feed nut b is fastened securely 90 in position.

The guide is of such length that when it occupies the assembled position described the rear end thereof lies substantially in the same transverse plane as the rear end of 95 the back head D. Thus arranged these ends of the back head and the guide serve as abutments for one side of a flexible connection e in the form of laminated springs comprising a plurality of plates f which extend laterally 100

of the feed nut *b* upon which they are arranged to support the rear end of the rock drill.

In order to maintain the weight of the flexible connection to a minimum the plates *f* 5 may be of substantially Y-shape having stems *g* wherein are formed apertures *h* to permit the stems *g* to be disposed upon the projecting end of the feed nut *b* between 10 the rear end of the guide and the nut *d* whereby they are clamped securely together.

The diverging wings or arms *j* of the Y-shaped plates *f* extend upwardly across the transverse medium plane of the rock drill 15 and are provided with perforations *k* through which extend the side rods *E* whereby the arms *j* of the plates *f* are clamped securely against the rear end of the back head *D*.

As a preferred form of construction the sleeve portion *W* of the guide is provided on its opposite sides with lugs *o* having apertures *p* extending longitudinally therethrough for the accommodation of the side rods *E* whereby the sleeve is clamped fixedly 20 between the flange *K* and the front end of the cylinder *B*.

In practice the present invention has been found to be highly efficient and to effect a considerable economy in the matter of maintenance of the drilling apparatus. It is a well known fact that the guide portion, such as the ribs *F* of the present structure, are exposed to severe usage and to consequent great wear. This is a factor which in structures wherein the guide ribs form an integral portion of the cylinder *B* is the cause of considerable expense since, in such structures, whenever the guide ribs become worn 25 to a state of unserviceability it becomes nec-

essary to discard the entire cylinder. Constructed as in the present invention, whenever the guide ribs become worn only the comparatively inexpensive guide need be replaced.

Another highly desirable advantage is that, owing to the provision of the flexible connection *e*, any variations within practical limits in the relative lengths of the guide and the casing parts of the rock drill, such as the cylinder and the back head, may be readily compensated for by the flexibility of the plates comprising the connection *e*.

I claim:

1. In combination, a rock drill having a plurality of casing parts, a guide for the rock drill, means on the guide being interposed between adjacent casing parts, clamping means for securing the first-mentioned means and the casing parts together, and a flexible connection on the clamping means and being secured to the guide by the clamping means to support the rear end of the rock drill.

2. In combination, a rock drill, a guide for the rock drill, means on the guide forming a casing part of the rock drill, a plate spring secured to the rear end of the guide to support the rear end of the rock drill, and bolts for clamping the said means and the plate spring to the rock drill.

3. In combination, a rock drill, a guide for the rock drill, a sleeve integral with the guide forming a casing part of the rock drill, a laminated plate spring on the rear end of the guide to support the rear end of the rock drill.

In testimony whereof I have signed this specification.

EDWARD F. TERRY.
